UNITED STATES PATENT OFFICE.

WILLIAM F. HARTHUN, OF NEWPORT, KENTUCKY.

RECORDING AND EXHIBITING DEVICE.

1,414,406.

Specification of Letters Patent. Patented May 2, 1922.

Application filed July 27, 1921. Serial No. 437,968.

To all whom it may concern:

Be it known that WILLIAM F. HARTHUN, a citizen of the United States, residing at Newport, in the county of Campbell and State of Kentucky, has invented certain new and useful Improvements in a Recording and Exhibiting Device, of which the following is a specification.

My invention relates to a device for advancing a strip or sheet, containing data, or upon which data is to be written, or both, and is adapted for use in connection with a telephone, while not restricted to this use.

An important object of the invention is to provide a device of the above mentioned character, having means whereby a flexible strip or sheet may be advanced in either direction, for exposing a selected portion of the strip, the advancing means being simple in construction, and highly convenient to operate.

A further object of the invention is to provide a device of the above mentioned character, having its parts arranged in a compact manner, whereby they may be enclosed within a casing or housing, suitable for association with a telephone.

A further object of the invention is to provide simple and reliable means for shifting the operating gear into engagement with either winding gear, and for locking the operating gear in the shifted position.

Other objects and advantages of the invention will be apparent during the course of the following description.

In the accompanying drawings forming a part of this specification, and in which like numerals are employed to designate like parts throughout the same,

Fig. 1 is a front elevation of a device embodying my invention,

Fig. 2 is a similar view, with the casing shown in section, to illustrate the interior mechanism,

Fig. 3 is a transverse vertical section taken on line 3—3 of Fig. 2,

Fig. 4 is a similar view taken on line 4—4 of Fig. 2,

Fig. 5 is a similar view taken on line 5—5 of Fig. 2,

Fig. 6 is a horizontal section taken on line 6—6 of Fig. 2,

Fig. 7 is a similar view taken on line 7—7 of Fig. 2,

Fig. 8 is a perspective view of a shifting arm, and

Fig. 9 is a similar view of a bracket and associated element.

In the drawings, wherein for the purpose of illustration is shown a preferred embodiment of my invention, the numeral 10 designates a casing, which may be formed of sheet metal or the like. This casing is preferably rectangular, excepting for an upper inclined portion 11, having a main opening 12 formed therein. The casing 10 may be formed in any suitable manner, but it is preferred that one side 13 of the casing be removable, and held in place by screws 14 or the like. The invention is of course not restricted to the use of any particular type of casing. The main opening 12 may be covered by a removable strip 15, formed of celluloid or the like, and which is adapted to be held over the opening 12 by insertion behind leaf springs 16.

Arranged within the casing 10 is a vertical supporting frame 17, held stationary therein by screws 18 or the like. The frame 17 embodies vertical sides 19 and 20.

Arranged within the supporting frame 17 are upper and lower spools or rolls 21 and 22, as shown. These spools preferably have rings 23, secured to the ends thereof, having radial flanges 24. Each spool has pivot elements 25 and 26, suitably secured to the ends thereof, and journaled in opening 27, formed in the sides of the frame 17. The pivot elements 26 are provided near their outer ends with annular grooves 28, to receive friction leaf springs 29, which serve to prevent the spools from turning too freely, preventing accidental movement. The pivot element 26 of the spool 21 has a gear 30 rigidly mounted thereon, between the end of the spool and the side 20 of the frame, and the pivot element 26 of the lower spool has a similar gear 31 rigidly mounted thereon.

The spools 21 and 22 are provided with longitudinal slits 32 and 33 respectively, adapted to receive the ends of a flexible strip or sheet 34, while these ends may be secured to the spools or rolls by any other suitable means. The strip 34, Fig. 2, may be transversely lined or ruled, at 35, for receiving the desired data, and the spaces formed by these transverse lines may be designated alphabetically, or sets of these spaces designated by the same letter, and the sets arranged in alphabetical order. It is obvious that the device may be used with other forms of strips, sheets, or charts 34.

The strip 34 passes over a transverse writing table or plate 36, arranged directly beneath the opening 12. This table or plate is carried by a pair of arms 37, engaging the outer surfaces of the sides 19 and 20 and secured thereto by screws 38 or the like. The arms 17 are bent inwardly near their rear ends, forming shoulders 39, engaging the rear edges of said arms 19 and 20, and the shoulders 39 carry apertured extensions 40, pivotally receiving the shaft 41 of a guide roller 42. As shown in Fig. 5, the strip 34 passes from the table 36 and over the guide roller 42 and then to the spool or roll 21.

15 The driving means for the spools or rolls includes a shiftable gear 43, which is rigidly mounted upon a shaft 44. This shaft is journaled in a sleeve bearing 45, carried by a slide 46, with which it is preferably integral. The side 20 has a slot 47, so that the shaft 44 may be shifted longitudinally of the frame 17, there also being a slot 48 in the side 13. A knob or head 49, preferably milled, is rigidly secured to the outer end of the shaft 44, and a washer 50, surrounds the bearing sleeve 45, and is shiftable over the slot 48. The numeral 50' designates a shifting arm, Fig. 8, having an eye 51 bent or formed upon one end thereof, which eye surrounds the sleeve bearing 45, and is preferably clamped thereto. The shifting arm 50 is arranged inwardly of the side 13, and carries a pin or stud 52, extending through an S-shaped slot 53, and provided with an exterior knob or button 54. The S-shaped slot 53 is provided near its ends with depressions 54 and 55, whereby the shank 52 may be locked therein. By operating the shifting arm 50, the gear 43 may be shifted into engagement with either gear 30 or 31, and locked in such engagement.

45 The slide 46, to which the bearing sleeve 45 is rigidly mounted, operates within the pockets 55' of brackets 56. The ends of these brackets straddle the side 20, and are clamped or otherwise rigidly secured thereto. The brackets 56 are provided with eyes 57 for holding the ends of the leaf springs 29. The numeral 58, designates a suitably supported pawl, preferably resilient, engaging the gear 30, to permit the same rotating in the direction of its arrow, but preventing rotation in an opposite direction. The gear 31 is engaged by a similar pawl 59, preventing back 55 rotation.

60 The casing 10 may be supported by any suitable means, and for this purpose I have provided the same near its top and bottom and adjacent its back with ears 60, having key-hole openings 61. These openings may receive hooks, screws or the like. I may employ an upper clamp bracket 62, having a headed screw or element 63, to enter the key-hole opening in the upper ear 60. The 65 clamp bracket 63 has a clamping bolt 64,

having screw threaded engagement therewith. The numeral 65 designates a co-acting clamp bracket, having a headed screw or element 66, to enter the key-hole opening 61 in the lower ear 60. A clamping screw or bolt 67 is carried by the bracket 65. These brackets may be used when the device is to be secured to a telephone, at a pay station, but it is obvious that the invention is in no sense restricted to the use of these brackets, as any suitable form of supporting means may be employed.

70 The operation of the device is as follows: When the shifting arm 50' is moved upwardly, so that the shank 52 engages in the upper depression 54, of the slot 53, the gear 43 will engage the gear 30. The knob 49 may now be turned clockwise, and will rotate gear 30, gear 30 being held against turning movement in a reverse direction. The 85 strip 34 is accordingly advanced upwardly, and the desired portion thereof brought beneath the opening 12. Suitable data may be written upon the strip through the opening, as this portion of the strip is directly above 90 the table 36. Should it be desired to advance the strip in an opposite direction, the shifting arm 50' is moved downwardly, and the shank 52 held in the lower depression 55, the gear 43 then engaging the gear 31. The gear 43 now engages gear 31, and when the knob 49 is turned clockwise, the strip 34 will be fed downwardly.

95 It is to be understood that the form of my invention herewith shown and described, 100 is to be taken as the preferred example of the same, and that various changes in the shape, size, and arrangement of parts may be resorted to without departing from the spirit of my invention or the scope of the 105 subjoined claims.

Having thus described my invention, I claim:

1. In a device of the character described, 110 a frame, rolls pivotally mounted within the frame in spaced relation and adapted to carry a flexible strip or sheet, gears secured to the ends of said rolls, a casing enclosing the frame and having an opening through which the strip or sheet is visible, said casing 115 being provided in one end with a slot having lateral extensions, a slide mounted upon one side of the frame to move longitudinally thereof, an operating gear carried by the slide and arranged between said gears, a 120 shifting arm connected with the slide and arranged between the frame and side of the casing, a lateral extension carried by the shifting arm and operating within said slot, and extending to the exterior of the casing 125 and adapted to be shifted into the lateral extensions of said slot to be locked therein, and separate means to turn the operating gear.

2. In a device of the character described, 130

a casing provided in one side with a slot, a frame held within the casing, rolls pivotally mounted within the frame in spaced relation and adapted to carry a flexible strip or sheet, gears secured to the rolls, a slide longitudinally movably mounted upon one side of the frame and carrying a sleeve bearing, a shaft rotatable within the sleeve bearing, a gear secured to the inner end of the shaft and adapted to engage the first named gears, a shifting arm secured to the sleeve bearing and provided with a lateral extension projecting outwardly through said slot, and a knob arranged exteriorly of the casing and secured to said shaft.

3. In a device of the character described, a casing having a main opening, a frame held within the casing, a writing plate extending transversely of the casing inwardly of and near the main opening, transverse arms secured to the ends of the writing plate and bent inwardly at points spaced from their rear ends for forming shoulders engaging about the edges of said frame, means to secure said arms to the frame, a guide roll pivoted between the rear ends of said arms, a pair of strip carrying rolls pivoted within said frame in spaced relation, one strip carrying roll being arranged between the writing plate and guide roll, and common means to turn either strip carrying roll.

In testimony whereof I affix my signature.

WILLIAM F. HARTHUN.
